ATTACHE CASE

Raymond P. Stoy, White Plains, N.Y., assignor to The Leather Specialty Company, Cincinnati, Ohio, a corporation of Ohio

Continuation-in-part of design application Ser. No. 87,717, Oct. 21, 1965. This application June 12, 1967, Ser. No. 7,452

Term of patent 14 years

(Cl. D87—5)

FIGURE 1 is a side elevational view of an attache case showing my new design, both sides of the case being identical.

The essential features of the design are shown in full lines.

This application is a continuation-in-part of my co-pending application Ser. No. D. 87,717, filed Oct. 21, 1965, now Patent No. D. 208,519, and entitled, attache case.

I claim:

The ornamental design for an attache case, as shown and described.
